MACHINE FOR SLITTING COVERS ATTACHED TO HEELS

Norwood H. Knowlton, Rockport, Mass., assignor
to United Shoe Machinery Corporation, Paterson, N. J., a corporation of New Jersey

Application March 25, 1932, Serial No. 601,096

29 Claims. (Cl. 12—42)

This invention relates to slitting machines and is illustrated as embodied in a machine for slitting the covers of heels of shoes.

In covering heels such, for example, as wood heels of women's shoes, it is customary to apply a single piece of covering material to the rear and to the sides of the heel. This piece of material is commonly referred to as a side cover and is of such a size that its top and forward marginal portions extend beyond the breast and the attaching faces respectively of the heel. After the side cover has been adhesively secured to the lateral portions of the heel, the top and forward marginal portions, which project beyond the attaching and the breast faces, are turned upon these faces respectively and are secured thereto.

Before turning the projecting portions of the side cover upon the sharply curved projecting part of the breast of a Louis heel, it is customary for the operator to slit these portions with the use of a pair of shears by a plurality of cuts disposed at substantially right angles to corresponding portions of the breast edges of the heel. This operation facilitates the laying of the marginal portions of the side cover upon the breast of the heel and insures that the covering will not be wrinkled where it is turned over the breast edges of the heel. It is the general practice, after the turned marginal portions of the side cover have been skived, to cover the breast of the heel by a separate piece of covering material which extends from one breast edge of the heel to the other and covers the turned marginal portions of the side cover.

The hand slitting method is slow and it frequently happens that the operator, in slitting the projecting marginal portion of the side cover, severs such portion up to the breast edge of the heel thereby exposing a small portion of the wood heel in the vicinity of the breast edge after the heel has been covered. It is especially desirable to control the depth of the cut when slitting covers preparatory to turning the marginal portions of the covers into heel cover receiving grooves or slots such as illustrated in United States Letters Patent No. 1,704,204, granted March 5, 1929 upon an application filed in the name of William H. Nutt, since part of the turned marginal portion of the cover serves as an outside cover for the lateral marginal portions of the breast of the heel. Accordingly, when covering this type of heel, it is particularly desirable to slit the heel covers more accurately than it is practical to do by the hand method.

It is an object of this invention to provide a machine which will quickly and effectively slit the projecting marginal portions of side covers of heels preparatory to turning such marginal portions upon the breasts of the heels.

It is another object of the invention to provide a machine for slitting the marginal portions of the side covers of heels preparatory to inturning and securing such marginal portions in heel cover receiving grooves or slots such as disclosed in the above-mentioned patent.

With these objects in view and in accordance with one feature of the invention there are provided a plurality of cutting edges, a gage to facilitate positioning the projecting margin of a cover attached to a heel properly with respect to the edges, means for guiding each of the cutting edges in a path spaced from the paths of movement of the others, and mechanism for operating said means thereby to cause the margin thus positioned to be slit. In the illustrated construction the cutting edges are formed at the ends of a plurality of blades or cutters which are slidably mounted in spaced grooves in a cylindrical supporting member. The gage is a stationary, but adjustable member having an arcuate operative face to engage the breast of the heel, and the cutters are reciprocated to slit the margin of the heel cover; and in order to facilitate rapid and accurate presentation of heels to the machine and to ensure that the slits shall be cleanly cut, there may be provided a side gage to cooperate with the arcuate breast gage and a cutting bed, which may be integral with the arcuate breast gage, to cooperate with the cutters.

It is desirable to hold the circularly arranged cutters with their edges in the same plane and to permit the cutters so held to be readily removed and replaced for the purpose of sharpening them or of replacing worn or broken cutters. To this end, in accordance with another feature of the invention, the cutters are held rigidly by a collar which engages opposite walls of recesses formed in the cutters and is mounted for reciprocation upon the cylindrical member in the grooves of which the cutters are slidably, there being a longitudinal groove or recess in the inner wall of the collar which, when the machine is at rest, may be brought into alignment with a selected groove in the cylindrical cutter-supporting member to permit the cutters to be removed and replaced one by one.

These and other features of the invention including certain details of construction and combinations of parts will be described as embodied

in an illustrated machine and pointed out in the appended claims.

Fig. 1 is a front view of the illustrated machine which is provided with right and left cover slitting units;

Fig. 2 is a perspective view of the left unit illustrated in Fig. 1, portions of the machine having been broken away in order to show operating parts thereof;

Fig. 3 is a sectional view taken along line III—III of Fig. 2;

Fig. 4 is a perspective view showing in detail mechanism for holding and for operating the slitting cutters;

Fig. 5 is a detail sectional view showing heel positioning gages which are of slightly different construction from those illustrated in Fig. 3;

Fig. 6 is a sectional view showing the machine equipped with another slightly modified form of heel gage; and

Fig. 7 is a perspective view showing a heel the projecting marginal portions of the side cover of which have been turned upon the breast of the heel.

The illustrated machine comprises a gage 20 constructed and arranged to engage the sharply curved part 22 of the breast of a Louis heel 24, the forward projecting marginal portions 26 (Fig. 2) of the side cover of which extend beyond the breast edges of the heel, and a side gage 28 for engaging a side of the heel to cooperate with the gage 20 in positioning the marginal portions 26 against a face or cutting bed or block 30 which supports or braces the marginal portions 26 one at a time as cutters or knives 32 are moved toward the bed 30 to form a plurality of slits preparatory to inturning the marginal portions 26 upon the breast of the heel as shown in Fig. 7.

The machine is mounted upon a standard 36 Fig. 1) to which is bolted a transversely extending frame 38 having at each of its end portions a forwardly extending boss 40. Each boss 40 is provided with a bore 42 shaped to receive a cylindrical member or bar 44 having a plane upper surface 46 against which a set screw 48 in threaded relation with the boss 40 may be forced to secure the bar 44 against movement after it has been positioned lengthwise in the bore 42. In order to permit the bar 44 after being removed from the bore 42 quickly to be replaced in its original position upon the boss 40, the bar 44 carries a collar 50 which is secured to the bar 44 by a screw 52 and having a rear face which engages the forward face of the boss 40.

As illustrated in Fig. 1 the machine includes left and right units A and B respectively for slitting the left and the right marginal portions 26 of covers. These units are substantially alike in construction, the only difference being that the parts are reversed so that the units may be placed close together and in opposed relation to enable the operator with a minimum amount of handling of the heel to slit the opposite marginal portions of the cover. Because of the substantial identity of construction of the units, it will be necessary to describe but one of the units in detail, it being understood, however, that for each part of one unit the other unit has an opposed but corresponding part.

The cutters or knives 32 are positioned for reciprocation in slots or guideways 54 which are disposed radially of the cylindrical member or bar 44 and extend lengthwise of the same. Each of these slots 54 is of a width corresponding approximately to the thickness of the cutters 32 each of

which, as best illustrated in Fig. 4, comprises a cutting edge 56, an elongated shank portion 58 which normally lies within the outside surface of the cylindrical member 44, and a pair of lateral extensions or flanges 60 which normally extend above the outside surface and through which the cutter is secured to a cutter operating collar 62 which will later be described in detail.

Secured to the inner ends of each of the bars 44 through a bolt 64 (Fig. 3) is a head 66 which in the illustrated machine comprises a sectional or inner portion 68 of the side gage 28 and the cutting bed 30. The heel breast engaging gage 20, which may be referred to as an arcuate member is secured to the head 66 by the bolt 64, and comprises an arcuate heel breast engaging surface 70 of frusto-conical form.

Each of the portions 68 of the heads 66 is also provided with radially disposed slots 72 (Fig. 2) which extend lengthwise of each head, the angular relation between these slots being such that when the head is positioned, as shown in Figs. 2 and 3, the slots 72 will be in alignment with the slots 54 of the bar 44 and will form therewith a plurality of continuous slots.

The cutters 32 which are reciprocated along their respective slots 54 and 72 to form the slits 34 in the projecting marginal portions 26 of the heel cover supported upon the cutting bed 30 are located in predetermined relation to each other lengthwise of the bar 44 through the cutter operating collar 62, the length of which is such that it will fit snugly between the spaced flanges 60 of the cutters 32. In order to mount the cutters 32 in the machine, each of the collars 62 is provided with a recess or slot 76 (Fig. 4) extending lengthwise through the collar 62, the slots 54 being moved successively by rotation of the bar 44 so as to be in alignment with the recess 76. Each of the cutters 32 may thus be readily inserted into the slots 54 and into the recess 76 and after they have been properly located lengthwise with respect to the collar 62, the bar 44 is turned to cause the flanges 60 of the cutters 32 to engage the opposite ends of the collar 62. Since the illustrated slitting operation is performed by the cutters which are located in the lower half of the bar 44, it is not essential that the cutters 32 of the upper half of the bar 44 be in lengthwise alignment. Accordingly, the upper portion of the rear face of the collar 62 (Fig. 4) is provided with a slightly dished portion 78 in order to expedite the placing of the cutters in the machine. Such a provision is especially useful in assembling the cutters since it frequently happens that the distance between the flanges 60 of the cutters is approximately equal to the length of the collar 62 and it is therefore necessary to force the cutter upon the collar. This is easily accomplished by providing the dished portion 78 since the length of the collar at its recess portion is shorter than the distance between the flanges 60.

The operator may therefore cause the flanges to over-ride the opposite ends of the collar 62 by turning the bar 44. It will be clear that as the bar 44 is turned the flanges 60 will be brought into contact with the opposite ends of the collar 62 and that the cutters will thus be clamped tightly to the collar.

In order to reciprocate the cutter carrying collar 62 along the cylindrical member or bar 44, the collar is pivotally secured to a bifurcated member 80 the rear end of which is provided with an eccentric collar 82 mounted upon an eccentric carried by a drive shaft 84. The drive

shaft 84 is supported for rotation in a rear bearing of the transversely extending frame 38 and in a front bearing 86 formed in a bracket 88 secured to the transversely extending frame 38 by 5 set screws 90. Power is supplied by a motor 92 operably connected through a belt 94 to a pulley 96 which drives a pinion 98 journaled in a housing portion 100 of the bracket 88 and meshing with another pinion 102 keyed to the rear end 10 of the shaft 84. The speed of rotation of the pulley 96 is fairly slow in order to permit the operator to present a heel to the machine between successive reciprocations of the cutters. The forward portions of each of the brackets 88 is provided with a drip pan 104 arranged to catch any lubricant which drops from the eccentric collar 82.

The side gage 28 illustrated in Figs. 3 and 6 comprises the inner part 68 and an outer part 106 having a heel engaging surface 108 which is substantially a continuation of a heel engaging face 110 of the inner part 68. The outer portion 106 is secured by a screw 112 to a rearwardly extending arm 114 bifurcated at its rear portion 25 to receive a clamp screw 116 which is in threaded relation with the boss 40. Although the gage 28 has been illustrated as comprising inner and outer parts 68 and 106 respectively, it will be understood that the inner part 68 may be laterally extended as illustrated in Fig. 5 so as to serve as a side gage without the use of an outer part 106, or the inner portion 68 may be reduced and the outer portion 106 may be extended toward the bar 44.

35 In order that the slits 34 may extend to within a predetermined allowable distance of the breast edge, the arcuate heel breast engaging faces 70 of the breast gage 20 are spaced from the path of movement of the cutting edges of the cutters 32. The illustrated space 118 formed between the cutting bed 30 and the side gage 28 is of constant size, but, if desirable, that space may be varied by making the side gage 28 and the cutting bed 30 of separate parts adjustable relatively 40 to each other lengthwise of the bar 44.

45 The breast gage 20 is eccentrically mounted upon the bolt 64 in order that the distance of the lower effective gaging portion or arcuate surface 70 of the gage 20 from the path of movement 50 of the knives 32 may be varied thereby to control the distance at which the slits 34 terminate from the breast edge of the heel.

It will be noted that in Fig. 6 the breast gage instead of having a conical surface 120 extending approximately to the plane of the cutting bed 30 comprises a disk 122, the arcuate heel engaging portion thereof being spaced axially of the bar 44 from the plane of the cutting bed 30. Such a gage may be advantageously utilized in 60 slitting the projecting marginal portions of heel covers which are to be turned into heel cover receiving grooves 124 formed in the breasts of heels and described in the above-mentioned United States Letters Patent No. 1,704,204. The heel engaging portion of this modified form of breast gage 20 instead of engaging the breast adjacent to the breast edge, engages the breast at a substantial distance from that edge in order to avoid interference with the heel cover receiving grooves 124.

70 It will be noted that the middle portion 126 of the breast of the heel is substantially straight transversely thereof while the sharply curved portion 22 is of convex curvature transversely of the breast. If, therefore, the slits 34 are to ter-

minate at the same distance from the breast edge, it will be clear that the portion of the arcuate face 70, which engages the sharply curved portion 22 of the breast of the heel, should be located nearer to the path of movement of the knives 32 than the portion of the arcuate face 70 which engages the middle portion 126 of the breast of the heel. By mounting the gage 20 eccentrically with relation to the axis of the cylindrical member 44, the portion of the arcuate face 70, which engages the sharply curved portion 22 of the breast of the heel, is arranged slightly nearer to the cutters than the portion of the arcuate face 70 in contact with the middle portion 126 of the breast of the heel. 15

The breast gage 20 instead of being constructed separately from the cutting bed or block 30 may be formed integral therewith as illustrated in Fig. 5. In such a construction the cutting bed 30 is preferably formed separately from a side gage 127 which is substantially similar to the inner portion 68 of the side gage 28, except that it extends laterally of the cylindrical member 44 to such an extent that it is unnecessary to use therewith an outer portion 106 of the side gage 25 such as illustrated in the other figures. The heel engaging surface 128 of the combined gage and cutting bed 130 is of conical form and serves as a support for the breast of the heel, the combined member being eccentrically mounted in 30 order that the effective heel engaging portion thereof may be adjustably spaced with relation to the path of movement of the knives 32.

In order to form slits 34 in the projecting marginal portions 26 of a side cover attached to a 35 heel, the operator positions the heel adjacent to one of the units A or B by engaging the breast of the heel with the breast gage 20 and by engaging a side of the heel with the side gage 28. As above stated, the speed of the cutter is so timed 40 that the operator may position a heel between successive reciprocations of the cutter. When the heel has been positioned, the cutters 32 are moved lengthwise of the bar 34 and slit the marginal portion 26 which is braced or supported 45 by the cutting bed 30. The heel is then presented to the other unit to slit the opposite marginal portion of the side cover.

Having thus described my invention, what I claim as new and desire to secure by Letters 50 Patent of the United States is:

1. A machine of the class described having, in combination, a plurality of cutting edges, means for guiding each of the edges in a path spaced from the paths of movement of the others, a gage 55 for positioning the projecting margin of a cover attached to a heel with respect to the paths of movement of said cutting edges, and mechanism constructed and arranged to move said cutting edges simultaneously along their respective paths 60 thereby to slit the margin of the cover simultaneously at a plurality of places to facilitate the folding of the cover around the heel.

2. A machine of the class described having, in combination, a plurality of cutting edges, means for guiding each of the cutting edges in a path spaced from the paths of movement of the others, a gage provided with a convex portion for positioning the projecting margin of a cover attached to a heel with respect to the paths of movement of the cutting edges, a support for said projecting margin, and mechanism constructed and arranged to move said cutting edges simultaneously along their respective paths relatively to the support to slit the margin of the cover simul- 75

taneously in a plurality of places thereby to facilitate the folding of the cover around the heel.

3. A slitting machine having, in combination, a gage constructed and arranged to engage the breast of a heel beyond a breast edge of which a marginal portion of a side cover projects, cutting edges arranged in a curved pattern, means for guiding each of the cutting edges in a path spaced from the paths of movement of the other cutting edges, and mechanism constructed and arranged to move said cutting edges simultaneously along their respective paths to slit said marginal portion thereby to facilitate the laying of the projecting marginal portion of the cover upon the breast of the heel.

4. A slitting machine having, in combination, a gage having a curved surface constructed and arranged to engage a sharply curved portion of the breast of a heel a marginal portion of the side cover of which projects beyond a breast edge of the heel, slitting cutters, mechanism for guiding each of the cutters in a path spaced from the paths of movement of the others, said gage having a face arranged to support the marginal portion of the side cover, and mechanism for moving the cutters along their respective paths to cause the same to cooperate with said face to slit the marginal portion by a plurality of cuts preparatory to folding the same upon the breast of the heel.

5. A slitting machine having, in combination, gages constructed and arranged respectively to engage the breast and a side of a heel a marginal portion of the side cover of which projects beyond one of the breast edges of the heel, a support for the marginal portion, and cutters constructed and arranged to slit the marginal portion of the side cover positioned relatively to the support by said gages by a plurality of cuts extending at substantial angles to the breast edge of the heel.

6. In a slitting machine, a member constructed and arranged to engage the projecting portion of the breast of a Louis heel beyond a breast edge of which a marginal portion of a side cover of the heel projects, a plurality of cutters, said member having a face constructed and arranged to support the marginal portion of the cover and a plurality of slots to receive said cutters, and means to produce relative movement between the cutter and the member to cause the cutters to form in the marginal portions slits extending at substantial angles to the breast edge thereby to facilitate the inturning of the marginal portions upon the breast of the heel.

7. In a slitting machine, a gage having a curved surface constructed and arranged to engage the sharply curved portion of the breast of a Louis heel a marginal portion of the side cover of which projects beyond a breast edge of the heel, a support for the marginal portion of the cover, a gage to engage a side of the heel and shaped and arranged to cooperate with the first-named gage in positioning the projecting marginal portion in predetermined relation to said support, and cutters movable relatively to the support to slit the projecting portions to facilitate the inturning of the same upon the sharply curved portion of the breast of the heel.

8. In a slitting machine, a gage having a curved surface constructed and arranged to engage the sharply curved portion of the breast of a Louis heel a marginal portion of the side cover of which projects beyond a breast edge of the heel, a cutting bed having a plurality of slots, a gage con-

structed and arranged to engage a side of the heel and to cooperate with the first-named gage in positioning the projecting marginal portion in predetermined relation to said cutting bed, and cutters movable relatively to the cutting bed to slit the projecting portions to permit the same to be smoothly inturned upon the sharply curved portion of the breast of the heel.

9. In a slitting machine, a disk having an out-curved edge constructed and arranged to engage a sharply curved portion of a Louis heel a marginal portion of the attached side cover of which projects beyond a breast edge of the heel, said disk having a side face constructed and arranged to support the projecting marginal portion of the cover, a plurality of cutting edges, mechanism for guiding each of the cutting edges in a path spaced from the paths of movement of the other cutting edges, and means to move the cutting edges along said paths relatively to the disk thereby to form a plurality of slits substantially simultaneously in the projecting marginal portion supported by said face.

10. A slitting machine having, in combination, a cylindrical member provided with a plurality of circumferentially spaced slots extending lengthwise thereof, a plurality of knives one of which is positioned in each of the slots, said member comprising an arcuate gage constructed and arranged to engage the sharply curved portion of the breast of a heel having a marginal portion of its side cover projecting beyond a breast edge of the heel and having a face to engage said marginal portion, and means to move said knives along the slots to form in the projecting portion supported by said face a plurality of slits disposed at substantial angles to the breast edge to facilitate the laying of said marginal portion upon the breast of the heel.

11. In a slitting machine, a cylindrical member having a plurality of radially disposed guideways extending lengthwise of said member, a disk provided with guideways which are aligned with the guideways of said member and being constructed and arranged to engage the sharply curved portion of the breast of a heel having a marginal portion of its side cover projecting beyond a breast edge thereof, said disk having a face to engage said projecting marginal portion of the cover, and knives mounted for movement in the guideways to sever the marginal portion of the cover supported by said face by a series of cuts disposed at substantial angles to the breast edges.

12. In a slitting machine, knives, a pair of disks spaced from each other and provided with aligned slots, one of said disks being smaller than the other and having an edge constructed and arranged to engage the sharply curved portion of the breast of a heel having a marginal portion of its side cover projection beyond a breast edge of the heel and the other disk having a face constructed and arranged to engage a side of the heel and to cooperate with the other disk in positioning the heel relatively to the knives, and means to secure a relative movement between the disks and the knives to cause the knives to sever the projecting marginal portion of the cover.

13. A slitting machine having, in combination, a cutting block, knives constrained for movement in a path toward and away from said block, a gage having an arcuate face to engage the breast of a heel and spaced from the path of movement of the knives, and a member having a face inclined to and projecting beyond the

arcuate face with respect to the path of the knives and constructed and arranged to cooperate with said gage in positioning a projecting marginal portion of the cover attached to the heel relatively to the block.

14. A slitting machine having, in combination a cutting block having a plurality of slots formed therein, knives constrained for movement in a path toward and away from said block, a gage

10 having a conical face to engage the breast of a Louis heel and spaced from the path of movement of the knives, and a member having a face inclined to and projecting beyond the conical face with respect to the path of the cutter and constructed and arranged to cooperate with said gage in positioning a projecting marginal portion of a side cover attached to the heel relatively to the block.

15. A machine for slitting covers secured to heels having, in combination, a heel cover supporting block provided with a plurality of slots, a plurality of knives constructed and arranged for movement through the respective slots, said block comprising an arcuate heel breast engaging face spaced from the path of movement of the knives, and a member spaced from and disposed at an angle to as well as extending beyond said face and constructed and arranged to engage a side of a heel the breast of which is in engagement with said arcuate face to cooperate with said arcuate face in positioning the marginal portion of a side cover projecting beyond a breast edge of the heel against said block as the knives are moved along the slots to slit the marginal portion by a plurality of cuts disposed at substantial angles to the breast edge.

20 16. In a slitting machine, a plurality of knives mounted for movement in fixed paths, a gage having an arcuate face spaced from said paths and constructed and arranged to engage the breast of a heel, a member spaced from the arcuate face in a general direction lengthwise of said paths and extending beyond the arcuate face in a direction at right angles to said paths, a cutting block, said member being constructed and arranged to engage a side of the heel and to cooperate with the gage in positioning a projecting portion of a side cover attached to the heel relatively to the cutting block, and means to move the knives in said path and against the block to sever the projecting marginal portion of the cover.

25 17. In a slitting machine, a plurality of knives mounted for movement in fixed paths, a cutting block having a plurality of slots, a gage having a conical face spaced from said paths and constructed and arranged to engage the breast of a Louis heel, a member spaced from the conical face in a general direction lengthwise of said paths and extending beyond the conical face in a direction at right angles to said paths, said member being constructed and arranged to engage a side of the heel and to cooperate with the gage in positioning a projecting portion of the cover applied to the heel relatively to the cutting block, and means to move the knives in said paths and into the slots of the cutting block to sever the projecting portions of the cover.

30 18. In a slitting machine, a plurality of knives mounted for movement in fixed paths, a cutting block, a gage having a conical face spaced from said paths and constructed and arranged to engage the breast of a Louis heel, a member spaced from the conical surface in a general direction lengthwise of said paths and extending beyond

the conical surface in a direction at right angles to said paths, said member being constructed and arranged to engage a side of the heel and to cooperate with the gage in positioning a portion of a cover attached to the heel and projecting beyond the breast of the same relatively to the cutting block, said conical face being mounted for adjustment toward and away from the path of movement of the knives, and means to move the knives in said path and against the block to sever the projecting portion of the cover.

35 19. A slitting machine having, in combination, a member having a convex surface constructed and arranged to engage the sharply curved part of the breast of a heel having a marginal portion of its side cover projecting beyond a breast edge of the heel, a gage spaced from and projecting beyond said surface and shaped to engage a side of the heel, said member having a face disposed at an angle to the convex surface and provided with a plurality of slots, and a plurality of knives constructed and arranged for movement to enter the slots to slit the marginal portion of the cover positioned upon said face, said convex surface being spaced at a predetermined distance from the path of movement of the knives to insure that the slits formed in the projecting marginal portion will extend only to a desired depth.

40 20. A slitting machine having, in combination, a cylindrical member provided with a plurality of slots extending substantially parallel to an element of the member, a knife constructed to fit in each of the slots and mounted for sliding movement therein, a cutting block having a supporting surface, a cutter operator to move the knives in the slots toward and away from the cutting block, a gage having a face curved about an axis disposed parallel to said slots and spaced laterally from the path of the cutting edges of the knives, a rest spaced lengthwise of the path of movement of the knives from the face of the gage and extending at an angle to the path of movement of the knives, and means to move the knives toward and away from the block.

45 21. A slitting machine having, in combination, a bar, members spaced lengthwise of the bar and projecting different distances laterally of the bar to engage respectively the breast and a side of a heel having an attached cover a margin of which projects beyond the breast of the heel, said bar and said members being provided with aligned slots, knives mounted for movement in the slots, and means to operate the knives to slit the projecting margin thereby to facilitate the laying of said margin upon the breast of the heel.

50 22. In a slitting machine, a plurality of knives the central portions of the cutting edges of which lie in a cylindrical surface, a cutting block, gages to engage a breast and a side of the heel a portion of the side cover of which projects beyond the breast edge of the heel to position the projecting portion of the cover relatively to the cutting block, and means to move the knives in paths substantially parallel to the elements of the cylindrical surface to sever the projecting marginal portion upon the block.

55 23. In a slitting machine, a bar having a plurality of circumferentially spaced slots extending lengthwise of the bar, a plurality of cutters located in the slots and having spaced portions extending laterally of and beyond the bar, a collar constructed and arranged to fit upon the bar and having a recess formed in its inner face and extending lengthwise to permit the blades to be positioned in said slots when the collar is mounted

upon the bar, and means to secure relative movement between the bar and the collar, said collar being of suitable length to fit snugly between the spaced lateral portions of the cutters thereby to 5 lock the cutters to the collar.

24. In a slitting machine, a bar having a plurality of circumferentially spaced slots extending lengthwise of the bar, a plurality of cutters located in the slots and having spaced portions 10 extending laterally of and beyond the bar, a collar constructed and arranged to fit the bar and having a recess formed in its inner face and extending lengthwise to permit the blades to be positioned in said slots when the collar is mounted 15 upon the bar, and means for producing relative movement between the bar and the collar, said collar being of a suitable length to fit snugly between the spaced lateral portions of the cutters thereby to lock the cutters to the collar and being of slightly reduced length at the recessed 20 portion thereof.

25. In a slitting machine, a plurality of cutters arranged in spaced relation about an axis and having their cutting edges disposed substantially radially with respect to said axis, a member constructed and arranged to engage the breast of a heel a marginal portion of the side cover of which extends beyond a breast edge of the heel, said member having a plurality of slots 25 constructed and arranged to receive the cutters and a face constructed to engage the marginal portions of the side cover when the breast of the heel engages said member, and means to move the cutters in paths extending substantially parallel to said axis to cause the cutters substantially simultaneously to enter the respective slots thereby to slit the marginal portion by a plurality of cuts each of which extends at a substantial 30 angle to the breast edge of the heel.

40 26. In a machine for slitting the projecting marginal portion of a Louis heel side cover, a cutting bed, an arcuate member constructed and arranged to engage the sharply curved part of the breast of the heel, a gage to engage a side of a 45 heel and to cooperate with the arcuate member

in positioning the marginal portion of the cover with the relation to the cutting bed and a plurality of knives mounted for movement in paths disposed at substantially right angles to the cutting bed and constructed and arranged to cooperate with the cutting bed to form a plurality of slits in the marginal portion of the cover. 5

27. In a machine for slitting a projecting marginal portion of a side cover attached to a Louis heel and extending beyond a breast edge of the heel, a heel gaging member having an arcuate face constructed and arranged to engage the breast of the heel, a plurality of cutting edges movable in spaced paths respectively relatively to said face for slitting the projecting marginal portion of the cover, and means for operating the cutting edges along said paths respectively to cause the same to slit the marginal portion, said face being spaced from the paths of travel of the cutting edges to insure that the slits formed in the projecting portion terminate at predetermined distances from the breast edge of the heel. 15

28. A machine for operating upon the cover of a heel a portion of the breast of which is substantially flat in its crosswise dimension and another portion of which is convex having, in combination, a plurality of slitting cutters the outer corners of which are arranged in a circle, and a breast gage having a heel breast engaging surface one portion of which is located farther outside the surface of the circle of the knives than is another portion. 20

29. A machine of the class described having, in combination, a cutter provided with a plurality of cutting edges, a gage to facilitate the positioning of the margin of a cover attached to and projecting beyond an edge of a face of a heel properly with respect to the slitting means, mechanism for guiding each of the cutting edges in a path spaced from the paths of movement of the other cutting edges, and mechanism for moving said cutting edges substantially simultaneously across said edge and over said face to slit the margin of the cover. 35
